H. S. ROYSE

MONEY SAFE

Filed Oct. 26, 1922

FIG-1

FIG-2.

FIG-3

INVENTOR:
HAROLD S. ROYSE.
BY *Whiteley and Buckman*
ATTORNEYS.

UNITED STATES PATENT OFFICE.

HAROLD S. ROYSE, OF MINNEAPOLIS, MINNESOTA.

MONEY SAFE.

Application filed October 26, 1922. Serial No. 596,977.

To all whom it may concern:

Be it known that I, HAROLD S. ROYSE, a citizen of the United States, residing at Minneapolis, in the county of Hennepin and State of Minnesota, have invented certain new and useful Improvements in Money Safes, of which the following is a specification.

My invention relates to money safes. It relates particularly to money safes into which the possessor may drop loose change and also bills from time to time until a sufficient amount is accumulated for deposit in a bank, which ordinarily would be the bank which puts out the money safe. An object is to provide a safe of this kind having a boxlike member for containing the money which may be readily formed from suitable material such as metal. Another object is to provide detachable booklike covers for the boxlike member which when attached and the box is lacquered in gold or gilded gives the safe the appearance of a book. The safe is thus given an attractive appearance and is convenient for carrying since it may be easily slipped into the pocket or into a handbag. An object in particular is to provide means for detachably securing the booklike covers to the boxlike member whereby the covers may be firmly held in place and can be readily detached when desired.

The full objects and advantages of my invention will appear in connection with the detailed description, and the novel features of my inventive idea will be particularly pointed out in the claims.

In the accompanying drawings which illustrate an embodiment of my invention, Fig. 1 is a plan view of the upper end of my safe showing the booklike covers partly open. Fig. 2 is a side elevational view with the rear portion of the safe shown in vertical section. Fig. 3 is a view in section on the line 3—3 of Fig. 1. Fig. 4 is a cross-sectional view of the securing means.

Referring to the construction shown in the drawings, the numeral 10 designates in general a box which may be constructed of any suitable material such as metal. This box has a side 12 which is hinged to the back and which is provided with any suitable lock so that a closure for the safe is thereby produced. The top of the box is provided with a slot 14 for the insertion of coins, removal of which is prevented by a

plurality of guard fingers 16 attached at opposite sides of the slot in customary or any convenient manner. The top of the box is also provided with a hole 18 which is too small to permit escape of even the smaller coins but is large enough to permit insertion of rolled up bills. The back of the box is provided with two perforations or openings 20 adapted to receive lugs 22 offset from a strip of metal 24 preferably by striking them out from the material thereof. The strip 24 is embedded in or secured in suitable manner to the back 26 of a pair of booklike covers 28 which are formed of suitable material such as leather or other flexible material. In order to secure the booklike covers in place on the box the lugs 22 are inserted in the perforations 20 and the ends of a flexible strip 30 are placed under the lugs. In order that the strip 30 may be better held in place, the ends thereof may be cut V-shaped as shown in Fig. 3 and in order that the strip may be readily removed so that the booklike covers may be detached from the box, the strip is provided with two projections 32 by means of which it may be flexed outwardly as shown in dotted lines in Fig. 2.

The operation and advantages of my invention will now be obvious. The covers may be readily detached at any time when the safe is open by removing the strip 30 in the manner indicated in Fig. 2, access to this strip being possible only when the safe is open. If a customer has been using a safe for a considerable length of time and closes out his account, and returns the safe to the bank, a new cover can immediately be attached at small cost, whereas if the cover were permanently attached to the safe the depreciation in a few years from safes turned in on closed accounts would be a considerable item.

I claim:

1. A money safe comprising a boxlike member, booklike covers for said member, lugs carried by the back of said covers adapted to pass through openings in the back of said member, and a flexible strip adapted to detachably engage said lugs.

2. A money safe comprising a boxlike member, booklike covers for said member, lugs carried by the back of said covers adapted to pass through openings in the back of said member, a flexible strip adapted to detachably engage said lugs, and pro-

jections on said strip to facilitate disengagement thereof.

3. A money safe comprising a boxlike member, booklike covers for said member, lugs carried by the back of said covers adapted to pass through openings in the back of said member, and a flexible strip adapted to detachably engage said lugs, said flexible strip having V-shaped ends for engagement with said lugs.

4. A money safe comprising a boxlike member, booklike covers for said member, a strip attached to the back of said covers, lugs carried by said strip adapted to pass through openings in the back of said member, and a flexible strip adapted to detachably engage said lugs. 15

In testimony whereof I hereunto affix my signature.

HAROLD S. ROYSE.
